UNITED STATES PATENT OFFICE.

ANSON B. MUNSON, OF STOCKTON, CALIFORNIA.

SCRAPER.

No. 926,997.

Specification of Letters Patent.

Patented July 6, 1909.

Application filed August 28, 1908. Serial No. 450,634.

To all whom it may concern:

Be it known that I, ANSON B. MUNSON, a citizen of the United States, residing at Stockton, in the county of San Joaquin, State of California, have invented certain new and useful Improvements in Scrapers; and I do declare the following to be a full, clear, and exact description of the same, such as will enable others skilled in the art to which it appertains to make and use the same, reference being had to the accompanying drawings, and to the characters of reference marked thereon, which form a part of this application.

This invention relates to improvements in scrapers and particularly to wheel carried scrapers, the object of the invention being to produce a simple and inexpensive scraper whereby the operator rides on the scraper and handles the same under all conditions without any assistance, the bowl of which may be actuated in such a semi-automatic manner as to fill the bowl easily and with the least possible resistance or friction to lift the scraper bowl with its load to a sufficient distance to clear the ground efficiently and when the same is filled and lifted to tilt the same backward to carry the dirt without waste, which tilting and lifting are accomplished in a semi-automatic manner with the driving power applied to the scraper and without the necessity of any manual labor whatsoever; also to produce a simple and effective means for dumping the contents of the bowl at any desired point. These objects I accomplish by means of a wheel truck having a double tongue, one slideable within the other, a supporting frame on said truck, a scraper bowl hung on said frame, a lever and chain mechanism connected with said bowl and said sliding tongue for lifting and tilting said bowl to carry the dirt, means for locking said sliding tongue when said bowl is raised and tilted, a lever mechanism for dumping said bowl from its tilted position; and by such other and further construction and relative arrangement of parts as will appear by a perusal of the following specification and claims.

In the drawings similar characters of reference indicate corresponding parts in the several views.

Figure 1 is a side elevation of the complete device as shown when ready for operation. Fig. 2 is a similar view showing the bowl

raised and tilted as when it is filled. Fig. 3 is a rear elevation of the scraper. Fig. 4 is a fragmentary view showing the sliding tongue mechanism. Fig. 5 is a top plan view of the wheel carrying frame with the scraper parts not shown.

Referring now more particularly to the characters of reference on the drawings 1 designates the wheels of the device having a forwardly projecting frame member 2 having a tongue 3 under which tongue 3 is slidably disposed a projected or auxiliary tongue 4 bearing against rollers 5 under the tongue 3. In the tongue 4 are two sockets 6 into which a pin 7 engages under certain circumstances as will appear, such pin 7 being pivoted on a weighted bell crank 8 fulcrumed upward from the frame 2 and having a foot tread member 9.

10 is a frame projecting upward from the frame 2, pivoted on the upper end of which is a bell crank 11 from which hangers 12 depend, such hangers supporting a scraper bowl 13 at a point a trifle forward of the center line thereof. From the upper end of the bell crank 11 a chain 14 extends under a sheave 15 and is connected to the inner end of the tongue 4. From the point of connection of the hanger 12 with the bowl 13, hangers 16 are pivotally connected with the frame 2.

Fulcrumed on the frame 10 is a lever 17 having a projecting operating handle 18, there being a link 19 connected between the said lever 17 and the rear end of the bowl 13.

20 are brake shoes having a brake rod 21 operated by a foot lever 22.

In operation the scraper bowl lies normally in the position shown in Fig. 1, and the forward motion of the device causes the said bowl to be filled with earth in the usual manner. Then when it is desired to raise and tilt the bowl for transportation purposes, the operator presses the member 9 downward, which action releases the pin 7 from the forward socket 6 and the motive power 100 pulls the tongue 4 forward independently of the tongue 3 until the rear socket 6 is reached when the pin is engaged into the same by means of a weight 8^a on the member 8, and then the whole device will be 105 again drawn forward. The operation of the tongue 4 as just described operates the chain 14 to cause the bell crank 11 to pull the link 12 upward which action raises and tilts the bowl 13 on its pivotal point "a", which ele- 110

vation and tilting into the position shown in Fig. 2 permits it to retain its entire load during transportation.

To dump the contents of the bowl 13 the operator grasps the lever 18 and pulls it upward to the position shown by dotted lines in Fig. 2. This action pulls the lever 17 forward which causes the link 19 to tip the bowl 13 on its pivotal point "b" to empty it. The handle 18 is then operated to return to normal which returns the bowl to the position shown in Fig. 2 and when it is desired to fill the same again the pin 7 is released from the rear socket 6 and the tongue 4 is operated rearward independently of the device until the pin 7 engages the forward socket again, which permits the bowl 13 to return to normal position.

The hanger 16 acts as a connection to force the bowl 13 to take its load and also gives added strength to the frame 2 when the device is being pulled forward.

From the foregoing description it will be readily seen that I have produced a scraper having an easy and effective means for raising and tilting and dumping and moving its load and depositing the same and one which substantially fulfills all the objects of the invention as set forth herein. All of the foregoing is calculated to pick up and place in position for moving a greater amount of material with less exertion than can be effected with any other scraper and with no loss of material while being moved to any distance desired.

While this specification sets forth in detail the present and preferred construction of my device still in practice, such deviations from such detail may be resorted to as do not form a departure from the spirit of the invention.

Having thus described my invention what

I claim as new and useful and desire to secure by Letters Patent is:—

1. A scraper comprising a wheel mounted frame, a tongue on said frame, a bowl swung on said frame and means operatively connected with said tongue for raising and tilting said bowl, as described. 45

2. A scraper comprising a frame, a tongue on said frame, an auxiliary tongue slidably independently under said first named tongue, a bowl on said frame, and means connected with said sliding tongue for raising and tilting said bowl, as described. 50 55

3. A scraper comprising a frame, a bowl swung therefrom, and means on said frame for raising and tilting said bowl into such position as elevates it from the ground and permits it to retain its load during transpor- 60 tation. 65

4. A scraper comprising a frame, a bowl suspended therefrom, a movable tongue under said frame and means for raising and tilting said bowl with the movement of said tongue, as set forth. 65

5. A scraper comprising a frame, a bowl suspended thereon, a bell crank on said frame, a link connecting one arm of said bell crank with said bowl and a chain on the other arm of said bell crank, adapted to operate the same, as set forth. 70 75

6. A scraper comprising a horizontal frame, an upwardly projecting frame thereon, a dependent lever on said frame, a projecting handle on said lever, and a link connecting said lever with said bowl, as set forth.

In testimony whereof I affix my signature in presence of two witnesses.

ANSON B. MUNSON.
